UNITED STATES PATENT OFFICE.

GEORGE H. MEEKER, OF MEDIA, PENNSYLVANIA.

ELECTRIC METER.

SPECIFICATION forming part of Letters Patent No. 690,450, dated January 7, 1902.

Application filed April 27, 1900. Serial No. 14,535. (No model.)

To all whom it may concern:

Be it known that I, GEORGE H. MEEKER, a citizen of the United States, residing at Media, in the county of Delaware, in the State of Pennsylvania, have invented certain new and useful Improvements in Electric Meters, of which the following is a full, clear, and exact description, reference being had to the accompanying drawings, of which—

10 Figure 1, Sheet 1, is a plan view, the top of the casing having been removed and the electrical connections with the parts omitted. Fig. 2 is a side elevation, the side of the casing having been removed. Fig. 3, Sheet 2, 15 is a diagrammatic representation showing the electrical connections. Fig. 4 is an enlarged section, as on line 4 4, Fig. 2, showing in plan the timing mechanism.

10 The object of my invention is to provide an improved joulemeter—*i. e.*, an electric meter that shall indicate or record automatically on a dial or the like the following product, *viz.*: amperes multiplied by volts multiplied by seconds (or other predetermined time units).

25 The invention, broadly considered, consists of a vibratory bar or the like, a movable part the extent of movements of which is governed by the electrical current passing through the service-line wires and which said movable 30 part and the said bar are so correlated that the extent of the vibrations of said bar are automatically limited by the position of said movable part, and means for imparting to said bar successive movements with relation to said movable part, together with indicating 35 mechanism adapted to be actuated by the vibrations imparted to the said bar.

30 The invention also consists in providing, in connection with the means for imparting to 40 said bar successive movements with relation to said movable part, suitable timing devices whereby the time intervals between the movements of said bar are inversely proportional to the electrical pressure of the service-line 45 wires.

45 The invention further consists of certain combinations and details of construction hereinafter fully pointed out.

50 Referring to the accompanying drawings, first with special reference to the diagrammatic Fig. 3, 1 designates a solenoid that is supported within a suitable casing 2 and is

connected in series in this instance, or it may be shunted in series, with the service-line wires *b b'*, which connect with the main-line 55 wires *a a'*. Thus the entire current or amperage (or any definite fraction thereof if said solenoid be shunted in series) of the service-line passes through this solenoid. As seen more clearly in Fig. 1, the solenoid 1 is formed 60 in the arc of a circle that is struck from the center of a vertical shaft 3, whose ends are journaled in bearings 3^a, secured to the casing 2.

Projecting from a hub 4, that is fixed on 65 shaft 3, is an arm 5, to the free end of which is secured a curved soft-iron core 6, which is concentric with the solenoid 1, into which it is adapted to enter to a greater or less extent, according to the magnetic force of the so- 70 lenoid, which varies with the amperage of the service-line, as hereinafter described. There also projects from the hub 4 a segment-plate 7, whose outer edge 7^a, of curvilinear form, as seen in Fig. 1, is suitably calibrated from 75 left to right to indicate amperes or other units of current measurement, as also hereinafter described. A torsional spring 8, Fig. 2, of shaft 3, the upper end of which spring is secured to hub 4 and the lower end to the lower 80 bearing 3^a, serves to maintain the core 6 normally—*i. e.*, when no current is being used—in the retracted position with relation to the solenoid, as seen in Figs. 1 and 2. It will be obvious that when any current is used on the 85 service-line the solenoid will induce partial rotation of the core 6 in the direction of the arrow in Fig. 1, and consequently of plate 7, corresponding with the strength of the current.

90 9 is a second solenoid, which is also secured to the casing 2 and in this instance occupies a plane at right angles to that of the first solenoid 1 and is at a level below that of the latter. This second solenoid is in the arc of 95 a circle whose center is the axis of a horizontal rotatable shaft 10, that is journaled in bearings secured to the casing. It (the said solenoid) is adapted to be automatically connected in multiple with the service-line wires 10 *b b'* when there is any load upon the line, as hereinafter particularly described.

11 is a vertical bar whose lower end is pivoted concentrically with the shaft 10. To

this bar is secured a curved soft-iron core 12, that bears a relation to the solenoid 9 similar to that of core 6 to the solenoid 1. The inner side of the upper portion of said bar 11 5 is closely adjacent to the curvilinear edge 7^a of the plate 7, as seen in Figs. 1 and 2. Normally—that is, when no current is passing through the solenoid 9—the bar 11, and consequently the core 12, are maintained in the re- 10 tracted position shown in said figures by means of a light spring 13, connecting said bar and a fixed post 14, Fig. 2, on the upper end of which latter is a projection 14^a, against which the bar is stopped. When the current 15 passes through the solenoid 9, as hereinafter described, the core 12 will be drawn into the former, and so the bar 11 will be rocked forward on its pivot against the slight stress of spring 13, the extent of the movement of the 20 bar being obviously limited by the then position of the curvilinear edge 7^a of the plate 7, which position will vary directly as the amperage of the service-line. The bar 11 has pivoted thereon a pawl 16, that is adapted to 25 engage a tooth of a ratchet-wheel 17, which is mounted upon the rotatable shaft 10, all as seen in Figs. 1 and 2. The said shaft also carries a worm 18, Fig. 1, that engages teeth of a gear 19 on a vertical shaft 20, which is 30 journaled in bearings of the casing 2 and which has an index 21, Fig. 2, on its upper end, extending over a suitable dial 22. It is manifest that when the bar 11 is rocked forward the pawl 16, engaging a tooth of wheel 35 17, will rotate the latter and shaft 10 a certain corresponding extent, and by reason of the said worm-and-gear connection the index 21 will be correspondingly rotated. As before suggested, the extent of the forward rock of 40 the bar 11, and consequently that of the movement of the index 21, is determined and limited by that part of the curved edge 7^a of plate 7 then in the path of the said bar.

Before proceeding with the description of 45 the construction of the apparatus I shall explain the mode of procedure I employ in calibrating or obtaining the proper form of the plate edge 7^a in order to insure that the angular distance through which the bar 11 can 50 move at any instant shall be directly proportional to the current or amperage passing through the first solenoid 1 at such instant.

The correspondence of movement of the bar 11 to the current is secured by suitably 55 curving the plate edge 7^a, the curve being evolved in the following manner: The plate 7 is first shaped approximately to the required form. The edge 7^b of plate 7 is straight and coincides with a line drawn from the bar 60 11 to the center or axis of rotation of said plate, which line (and so the edge 7^b) is tangential to the arc of rotation of the bar 11, and the free end of said edge 7^b is adjacent to the said bar, as in Figs. 1 and 2. A current of known quantity—say five amperes— 65 is passed through solenoid 1, which will cause a corresponding in-draw of the core 6 and a

definite rotation of plate 7. The point in the edge of the latter that is now presented to the bar is marked. A line is then drawn 70 from the axis of rotation of said plate to the point on the edge of the plate that is then presented to the bar, which line will be tangential to the arc of rotation of bar 11. This line may be termed the "five-ampere" line. 75 Then pass a current through solenoid 1 of, say, ten amperes and draw a line similar to the five-ampere line, and so on until a sufficient number of tangent lines have been drawn. The unit of angular rotation of said 80 bar having been selected, for example, a movement of the bar that would cause the wheel 17 to rotate a distance equal to that between, say, five teeth of the wheel would result from five amperes. Then mark off on 85 the straight or tangential edge 7^b of the plate such distance from the free end of the latter adjacent to the bar as shall be equal to the angular distance of travel of the bar in advancing five teeth of said wheel. Then mark 90 off on said edge a point corresponding to the travel of the bar in advancing ten teeth of the wheel, and so on, corresponding with the number of ampere tangent lines laid off, as before mentioned. Then with the dividers, 95 using the said axis of rotation of the plate as a center, transfer the points on the tangent edge 7^b to the respective corresponding radial lines. Finally, having determined a sufficient number of points on the radial tangent lines they are connected by a line which will be the line of the required edge 7^a of the 100 plate. The surplus material outside of this line is cut away; but it is important that the original weight of the plate shall be maintained by compensating for the portion removed. Assuming the electrical pressure or 105 voltage on the service-line to be constant and the amperage of the load variable, it is clear that if electrical impulses be given to 110 the solenoid 9 at equal intervals of time then the index 21 and dial 22 of the apparatus, hereinbefore described, would show the desired metrical resultant—that is, volts multiplied by amperes multiplied by seconds, 115 (time periods;) but in practice the pressure or voltage is not constant, but frequently varies. It is therefore necessary that there shall be given to the solenoid 9—in effect, to the bar 11—impulses so timed that the time 120 intervals between any two impulses shall be inversely proportional to the then voltage. I shall now describe a mechanism and devices which I have devised for imparting such impulses to the solenoid 9. 125

23 and 24 are two electromagnets, each separately connected in multiple with the service-line wires b b', as indicated in Fig. 3 and as hereinbefore particularly described, and the circuits of these magnets are adapted to receive the full electric pressure or voltage on the said wires. In front of these magnets, respectively, are pivoted armatures 25 and 26, one for each magnet, which are adapted 130

to vibrate between stops 27 and 28 for the armature 25 and stops 29 and 30 for the armature 26. The said armatures are normally—that is, when no current is passing through the service-line, and hence through the said magnets—held in contact with the rear stops 27 and 29, respectively, by suitable springs 31, one of which is seen in Fig. 2, that extend between the armatures and the posts, respectively, that support the rear stops.

33, Figs. 1 and 2, is a balance-wheel mounted upon a vertical arbor 34, that is journaled in a bearing of the casing and of a bracket 35, fastened to the latter. This wheel has secured to it a depending arm 36, to which is fastened a sheet or plate 37 of soft iron, constituting a "magnetic shield," which as said wheel is caused to oscillate will be brought opposite to—*i. e.*, in front of—the poles alternately of the magnets 23 and 24, as and for the purpose to be described. The torsional spring 38 of the balance-wheel tends to maintain the latter normally—that is, when no current is being used—in such position as to bring the plate 37 opposite to the pole of magnet 23, as seen in Figs. 1, 2, and 4.

Referring now to Fig. 3 and in part to Fig. 4, *a a'* are the main or feed wires, and *b b'* the service-line or house wires, as previously stated. The solenoid 1 is connected in series with the service-line wires *b b'*, and the solenoid 9 is connected in multiple with said wires, as also before mentioned and as hereinafter particularly described. A wire *c* leads from one of the service-wires *b* to the armature 25, and a wire *c'* leads from the other service-wire *b'* to solenoid 9. A wire *c²* from the other end of the latter solenoid connects with the forward stop 28 of the said armature 25. If this armature be brought against stop 28, obviously the circuit through solenoid 9 will be closed. A branch wire *d'* from wire *c'* leads to one end of the magnet 23 and wire *d²* from the other end of said magnet to the rear stop of armature 26. A wire *e'* branches from wire *d'* and leads to one end of magnet 24, and a wire *e²* leads to the rear stop 27 of armature 25. The wires *d'* and *e'* might be connected directly with the service-wire *b'* without materially affecting the result. A wire *d* connects wire *c* with armature 26. When the armature 25 is against the stop 27, the circuit of magnet 24 will be closed, and when armature 26 is against stop 29 the circuit of magnet 23 will be closed.

The foregoing are the positions of the armatures shown in the drawings, and no current being consumed on the service-line the plate 7 is at the zero-point, and the bar 11 is in the retracted position, and the cores of the two solenoids 1 and 9 are in the respective retracted positions shown. Also the balance-wheel 33 is in the position through the stress of its spring 38 in which the magnetic shield 37 is directly in front of the pole of magnet 23—that is, between the latter and the armature 25—as seen in Figs. 1, 2, and 4. If now a load—as, for

example, a number of lamps, as *x*, Fig. 3—be put upon the service-line, the core 6 will be drawn into solenoid 1 a certain distance and 70 the plate 7 correspondingly rotated, but the bar 11 remains in the vertical retracted position for the reason that at the instant no current is passing through the solenoid 9, the circuit of the latter being open because the 75 armature 25 is not against the stop 28. The circuits of magnets 23 and 24 are at this time closed. Consequently they will tend to attract the armatures 25 and 26, respectively. The armature 25, however, cannot move toward 80 its magnet 23 owing to the interposed magnetic shield, which cuts off or deflects the lines of magnetic force; but as soon as armature 26 moves forward from the stop 29 the circuit of magnet 23 is broken, and as at this moment the circuit of magnet 24 is still closed, owing to armature 25 remaining against its stop 27, the magnet 24, attracting the magnetic shield, draws it over into position in front of the said magnet 24, whereupon the 85 lines of magnetic force being deflected or cut off by said shield armature 26 swings back by the stress of spring 31 against stop 29 and closes the circuit of magnet 23. This 90 magnet now attracting its armature 25, the latter moves over against stop 28. This closes the circuit of solenoid 9, which then draws in its core 12, and so swings forward the bar 11 until it (the bar) comes against the curved edge 7^a of plate 7 at that point which 95 is then in the arc in which the bar swings. This movement of the bar rotates the ratchet-wheel 17 a definite distance, and so through the intervening mechanism the index 21. The magnetic shield is now caused by magnet 23 to swing back from magnet 24 to position in front of the former, whereupon armature 25 returns against its stop 27, thus 100 breaking the circuit of solenoid 9, and the bar 11 is retracted to the normal position 105 by the spring 13, and so on consecutively. It will be observed that with each both-way 110 oscillations of the balance-wheel and resulting to-and-fro movements of the magnetic shield an electrical impulse will be imparted 115 to the solenoid 9, and thus the bar 11 be rocked forward against the edge 7^a of plate 7. The frequency of these oscillations, and so the timing of the rocking of the bar 11, will depend upon the strength of the pull exerted at the 120 particular instant by the magnets 23 and 24 upon the magnetic shield, and this pull will vary with the quantity of electricity passing through the coils of these magnets. Since the resistance of the circuits of the latter are 125 constant, the currents will vary directly with the voltage or pressure of the service-line wires, and therefore the frequency of the oscillations of the balance-wheel will always be in direct proportion to the voltage. The 130 weight of the balance-wheel and the strength of the magnets 23 and 24 are so adjusted at the outset that with any predetermined unit of electrical pressure—say one hundred volts,

for example—the said wheel will make a both-way oscillation in a predetermined unit of time—say one second. Thus if a current of, say, two hundred bolts be passing through 5 the service-line the balance-wheel will make two both-way oscillations per second, thereby making and breaking the circuit of solenoid 9 twice each second, and so the bar 11 will be rocked twice in the second against the 10 edge 7^a of plate 7, (the position of which, as before explained, varies directly with the amperage,) and the required product or resultant—viz., amperes multiplied by volts (one hundred) multiplied by seconds—will be 15 shown on the dial by the index 21 through the operation of the mechanism intervening between the latter and the bar 11.

As it is not desirable that the circuit *c' c'* should be closed when there is no load upon 20 the line, I generally interpose in said circuit an automatic switch S, (indicated in Fig. 3,) itself connected in series with the service-line wire and adapted to automatically close the circuit when any load is placed upon the line 25 and to break the circuit when the load is removed. As such switches are well known, I have not deemed it necessary to particularly show or describe the same herein.

I do not limit myself to the precise construction and arrangement of the parts of 30 my invention hereinbefore described, as it will be obvious to those skilled in the art to which the invention pertains that the construction may be considerably varied to obtain 35 the ultimate result desired without departing from the principle of the invention. I further remark that the device is adapted for use with either direct or alternating currents and has a very small internal current 40 consumption.

Having thus described my invention, I claim as new and desire to secure by Letters Patent—

1. In an electrical meter, the combination 45 of the vibratory bar, or the like, a movable part, means whereby the extent of movement of which part is governed by the electric current passing through the service-line wires, said movable part and said bar being so correlated that the extent of the vibrations of 50 said bar are automatically limited by the position of said movable part, and means for imparting to said bar successive vibrations with relation to said movable part, the time 55 intervals between which vibrations are inversely proportional to the electrical pressure of said wires, together with indicating or recording mechanism adapted to be actuated by the vibrations imparted to the said 60 bar, substantially as and for the purpose set forth.

2. In an electrical meter, the combination 65 of an oscillatory part adapted to be controlled by the electrical current and actuated thereby, a reciprocating bar, or the like, occupying normally a definite position with relation to said oscillatory part, the extent of the re-

ciprocation of which bar is adapted to be limited by the position which said part is caused to occupy by the action of the said electrical current, means adapted to be actuated by the electrical current for imparting to said bar successive vibrations toward and against 70 said oscillatory part in intervals of time inversely proportional to the electrical pressure, means for returning said bar to the normal position after each of said vibrations, and mechanism connected with said bar for consecutively recording the extent of said vibrations, substantially as and for the purpose 75 set forth.

3. In an electrical meter, the combination of the solenoid, adapted to be connected in series with the service-line wires, the core adapted to oscillate in said solenoid, the plate 80 having the calibrated edge adapted to be oscillated by the movements of said core and in correspondence therewith, the vibratory bar, the solenoid adapted to be connected in multiple with the said service-line wires, the core adapted to oscillate in said solenoid and connected with said bar, the electromagnets connected with the service-line wires, armatures adjacent thereto, respectively, the magnetic shield adapted to oscillate in a path between 85 said armatures and magnets, stops between which the said armatures are adapted to vibrate, and the electrical connections of said magnets, armatures and stops, together with suitable indicating or recording mechanism adapted to be actuated by the vibrations of said bar, substantially as and for the purpose 90 set forth.

4. In an electrical meter, the combination 95 of an oscillatory part adapted to be controlled by the electrical current and actuated thereby, a vibratory bar, the solenoid, or the like, adapted to be connected in multiple with the service-line wires, and adapted to control the movement of said bar, means for automatically closing the circuit through said solenoid 100 when a load is placed upon the service-line wires, and for breaking the circuit when no load is upon said wires, together with suitable indicating or recording mechanism adapted to be actuated by the vibrations of said 105 bar, substantially as and for the purpose set forth.

5. In an electrical meter, the combination 110 of the vibratory bar, or the like, a movable part, means whereby the extent of movement of which part is governed by the electric current passing through the service-line wires, said movable part and said bar being so correlated that the extent of vibrations of said 115 bar are limited by the position of said movable part, the solenoid, or the like, for imparting vibrations to said bar and adapted to be connected in multiple with the service-line wires, the electromagnets also adapted to be connected in multiple with the service-line wires, the respective armatures adjacent thereto, their front and rear stops, and the electrical connections between said solenoid, 120

electromagnets, armatures and stops, whereby when the armature of either of said magnets is against its rear stop, the circuit of the other magnet will be closed and when against its front stop, the circuit of said other magnet will be open, and whereby also when one of said armatures comes against its forward stop it will thereby close the circuit through said solenoid; together with the magnetic shield adapted to automatically reciprocate

in a path between said armatures and magnets, substantially as and for the purpose set forth.

In testimony whereof I have hereunto affixed my signature this 10th day of April, 1900.

GEORGE H. MEEKER.
